ATTACHMENT FOR SEWING MACHINES

Isaiah S. Rickman, Williamsport, Pa.

Application October 31, 1951, Serial No. 254,068

1 Claim. (Cl. 112—208)

1

This invention relates to an attachment for sewing machines and has particular reference to a retardative element and actuating mechanism therefor, designed to maintain two pieces of fabric, such as a main body section and a pleat or the like, in proper alignment when same are being stitched together.

In the conventional method now in use for stitching two pieces of fabric together, the regulation feeder upon a machine is employed to draw the fabric under the presser foot and the needle. The action of this feeder is such that the lower layer of fabric has a tendency to creep as the two layers are being fed under the presser foot of the machine, to such an extent that the ends of two layers of fabric do not come into proper alignment. The end of the upper layer extending beyond the end of the lower layer of fabric, or in other words, the feeder in the conventional machine, as it draws the fabrics under the presser foot, causes the lower fabric with which it directly engages, to pull together and slightly crumple or creep, thereby drawing in the end of the fabric and out of alignment with the end of the upper layer.

The principal object of this invention is to provide a means which will overcome this objection or defect. This means comprises a retardative element engageable through the throat plate of the machine and adapted to horizontal and vertical reciprocal movement in line with the conventional feeder element, and moving simultaneously with it, but with opposite horizontal reciprocal movement.

Another object of this invention is the means employed to activate the said retardative element, said means comprises rods connecting the said retardative element to conventional operating parts of the machine to impart a reciprocal horizontal and vertical movement to same.

A further object of this invention is to provide a fabric retardative element which may be built into new machines or which may be readily attached to machines now in use.

A still further object of this invention is the provision of an organization in which the constituent elements are so arranged structurally and functionally as to assure improved results with materials and members which may be manufactured at reasonable cost, may be easily

5 assembled and which will be efficient in operation with minimum wear to the parts.

The best embodiment of the invention has been chosen for illustrative purposes, but this embodiment should be viewed as being illustrative only and not as limiting because obviously the invention is capable of other embodiments having revised details of construction, so long as they fall within the ambit of the appended claims.

10 The invention itself, however, both as to its organization and its method of operation, will best be understood from the following description of a specific embodiment when read in connection with the accompanying drawings, in which:

Fig. 1 is a partial plan or top view of the base plate at the sewing end of a sewing machine head and shows the throat and sliding plates in position.

15 Fig. 2 is a similar view but shows parts of the base plate broken away, the throat plate removed and the sliding plate partly pulled out, to disclose the parts directly below the base plate.

20 Fig. 3 is a sectional, elevational view taken along the line 3—3 of Fig. 2, looking in the direction indicated by the arrows and shows the relative position of the needle, needle bar and the presser foot.

25 Fig. 4 is an elevational end view of the base-plate of the sewing machine, parts being broken away.

30 Fig. 5 is a fragmentary detail, in elevation and partly in section, taken along the line 5—5 of Fig. 3.

35 Fig. 6 is a slightly enlarged sectional view of a fragmentary detail and is taken along line 6—6 of Fig. 3.

40 Fig. 7 is a top or plan view of the end portion of a base plate with parts broken away, similar to Fig. 2, but showing a slight structural modification.

45 Fig. 8 is a sectional elevational view taken along the line 8—8 of Fig. 7.

Fig. 9 is a fragmentary detail in elevation showing an upper and lower layer of fabric as they appear after being stitched together in a conventional machine.

Fig. 10 is a diagram, in plan, which will be further explained.

Fig. 11 is a view similar to that of Fig. 9 but

shows the upper and lower layers of fabric as they appear after being stitched by a machine which embraces the attachment which is the subject matter of this specification, and invention, and

Fig. 12 is another diagram, in plan, which will be further on explained.

Referring in detail to the parts, 11 designates the base plate of a sewing machine head. 12 and 13 are depending lugs integrally formed upon the base plate at its further end and are shown only in Figs. 3, 4 and 8. The lug 12 supports one end of an oscillating shaft 14 the opposite end of which is supported by a conical bearing member upon the end of a threaded bolt 15 which engages through a threaded bore in a lug 16 (Figs. 2 and 4). A nut 17 is provided to tightly lock the threaded bolt 15 securely in place. The lug 13 supports one end of a second oscillating shaft 18, the opposite end of which is supported by a conical bearing member upon the end of a threaded bolt 19 which engages through a threaded bore in a lug 20. A nut 21 provides a means for securely locking the threaded bolt 19 in place. The base plate 11 is formed with a cut out portion 22 open at the end 23 (Figs. 1, 2 and 7). A ledge 24 extends along both sides and across the rear circular portion of the cut out portion.

A throat plate 25 is secured to the ledge at the inner portion of the cut out 22 by means of countersunk screws 26. Along the ledges 24 at the sides of the cut out portion 22 are under cuts 27 conforming to the edges of a sliding plate 28, shown in closed position in Fig. 1 and in partly withdrawn position in Fig. 2. The throat plate 25 is provided with a needle orifice 29 and with a pair of elongated slots 30 and a pair of shorter slots 31 and 31' through which feeder elements engage as will be hereinafter explained.

Referring now to Figs. 2, 4 and 7, it will be observed that the oscillating shaft 14 has, integrally formed upon it, a pair of upright lugs 32 and 33 through which threaded bolts 34 and 35 respectively engage. The inner ends of the bolts 34 and 35 are each formed with conical bearing ends which engage a cross bar 36. Lock nuts 37 are provided to securely hold the threaded bolts 34 and 35 in place. Integrally formed upon and extending laterally from the cross bar 36 there is a connecting rod 38 terminating in a slot formation 39 which engages over a roller 40 (Figs. 2 and 7). The roller 40 is mounted upon a pin 41 which is in turn secured to a bracket arm 42 extending from and secured upon the oscillating shaft 18 and oscillates with same. To the upper surface of the connecting rod 38, there is attached a plate 43 which is secured to the connecting rod by means of screws 44. A portion of the plate 43 extends laterally from its attachment portion as at 45, and is formed with upstanding feed dogs 46 which have serrated upper edges 47. The said portions 46 are engageable through the aforementioned slots 30 and 31 formed in the throat plate 25 (Fig. 1). A bobbin casing 48, shown in outline only, is secured upon one end of a hook shaft 49 which is mounted in bearings (not shown) in a lug 50 depending from the base plate 11 at one end of same and suitably mounted in bearings, not shown, at its opposite end.

The above description has referred only to conventional parts in a sewing machine head which forms a part of a regulation machine in common use and forms no part of this invention except as it has cooperative relation with the attachment comprising this invention and which will now be described and operatively explained.

An elongated plate 151 formed with a slot 152, (Figs. 2, 3, 4 and 5) is bracketed from and secured to the oscillating shaft 14 by means of a projecting flange 153 and screws 154. A block 155 is slidably mounted upon the slotted plate 151 but is held against sliding movement by means of a bolt 156 formed with a head 157, extending through the block 155 (Fig. 6), encased by a spacer collar 158 which extends slightly beyond the face of the block, a washer 159 and a nut 160. This permits the block 155 to be adjusted along the slot 152 and then tightened in any selected position while at the same time allowing the block 155 to have a pivotal movement about the bolt 157 and its spacer collar 158. Attached to the block 155 is the depending end 161 of a connecting arm 162. The said depending end being slotted as at 163 and held securely upon the block by screws 164 which engage through the slot 163 and into the block 155 (Fig. 5). The arm 162 is of irregular shape and extends upwardly and then downwardly and terminates in a slotted end portion 165 which slidably engages a roller 166 upon a pin 167 which in turn is secured upon a bracket arm 168 attached to and extending from the oscillating shaft 18. The bracket arm 168 is formed of a flat strip adapted to encircle the oscillating shaft 18, as indicated at 168' and a bolt 168'' is employed to tighten the flat strap around the oscillating shaft 18. An L-shaped bracket arm 169 extends laterally from the arm 162 and is held thereon by means of screws 170 which engage through a slot 171 upon the L-shaped arm. A retardation element, comprising a plate 172 and upwardly projecting arms 174 having serrated upper edges 175 which are engageable through the slots 30 and 31' is attached to the free end of the L-shaped bracket 169, by means of the screws 173 (Fig. 2).

When two layers of fabric are stitched together by a sewing machine which does not include the attachment comprising this invention, the feeder invariably causes the lower fabric to creep ahead of the movement of the upper layer bringing the end of the lower layer out of alignment with the upper layer. This result is clearly shown in Fig. 9 where the upper layer of fabric is represented by the numeral 176 and the lower layer by the numeral 177. The parts of the mechanism indicated are those of a conventional sewing machine which is not equipped with the improved attachment comprising this invention. The overlapping edge of the upper layer is shown at 178. The lower layer which has been drawn in shows the edge 179 out of alignment with the edge 178. Fig. 10 shows the offset of the edges 178 and 179 when the lower layer 177 is caused to creep ahead of the upper layer 176 during the stitching action by the movement of the conventional feeder 46 with its serrated edges 47. Fig. 11 also shows the conventional machine and feeder but with the addition of the retardative member 174 of this invention. With this added retardative member the creeping movement of the lower layer is prevented and the two edges come together in perfect alignment, as indicated at 180 and 181 and as shown in plan in Fig. 12.

Figs. 7 and 8 show a slight structural modification in which a rod 182 is substituted for the arm 162 heretofore shown and described. The rod 182 is slidably and pivotally secured, as at 183, to an arcuate member 184 which is slotted at 185 and is secured to the oscillating shaft 14 by means of an attached flange 186 and screws 187. The opposite end of the rod 182 is pivotally attached at

188, to a plate member 189 and is adjustable thereon by means of a screw 190 which is threaded in the plate member 189 and engages through an arcuate slot 191 upon the plate 189. By tightening the screw 190, the rod 182 and the plate 189 are securely fastened together and are immovable with respect to one another. The plate projects outwardly at one point to form jaws and a slot 192 which slidably engages with the roller 166 upon a pin 167 which is in turn secured to the bracket 168.

A flat bar 195 having a slot 196 is adjustably attached to the plate 189 by means of screws 197 which engage through the slot 196 and are threaded into the plate 189. The upper end of the bar 195 extends approximately at right angles, into a platform formation 198 upon which there is attached the L-shaped bracket 169 which is secured thereon by the screws 170 engaging through the slot 171. To the outer, free end of the L-shaped bracket there is secured by means of the screws 173 the retardative element, hereinbefore mentioned, which comprises the base 172 and the upwardly projecting arms 174 having serrated upper edges 175.

As hereinbefore stated the retardative element comprises a multiplicity (usually three) of upstanding arms 174 having serrated upper edges 175 which project upwardly through slots 30 and 31', (Fig. 1) formed in the throat plate 25. The serrated edges 175 of the arms 174 may be of varying lengths to provide a staggered arrangement of the ends facing the needle opening 29 as shown. The upstanding arms 46 of the conventional feeder element must be shortened to allow sufficient space, in the slots 30, for the serrated edge portions 175 of the arms 174 of the retardative element. The front of the machine head at which an operator sits and faces the needle is indicated on the drawings by the letter F and as viewed in the drawings is at the right. When feeding a fabric into the machine and under the presser foot at the beginning of a stitching operation, the staggered ends of the serrated portions 175 of the arms 174 allows the conventional feeder unit to grasp the fabric and prevent the retardative element from drawing the fabric away from the needle when the machine begins to operate.

The conventional feeder unit, comprising the arms 46 with the serrated upper edges 47 is alternately given a forward and rearward movement by means of its connection through the cross bar 38, coaxing with the conventional oscillating shaft 14. When the feeder element has moved rearwardly (to the left as viewed in the drawings) and has reached its extreme rearward position, the bracket arm 42, oscillating with the oscillating shaft 18, moves the pin 41 attached to its free end, downwardly and the roller 40 upon the pin, engaging the slotted end 39 of the cross bar 38 lowers the feeder unit below the upper surface of the throat plate 25 as clearly shown in Fig. 8. While the feeder unit is in this lowered position the oscillator shaft 14 reverses its direction to move the feeder unit forward or to the right. At this point the oscillator shaft 18 also reverses its direction of movement and moves the feeder unit upwardly to bring its serrated edges 175 up against the fabric and presser foot 47, as indicated by dotted lines 46' in Fig. 9. The oscillating shaft 14 and the connecting cross bar 38 now moves the feeder unit rearwardly or to the left until it reaches the position shown by full lines in Fig. 9. The descrip-

tion and operation of the feeder unit, just recited, concerns the regulation mechanism in use on all conventional machines and is not a part of this invention but is shown and described so that a clear understanding of its cooperative action with the retardative element which is the subject of this invention.

The retardative element, as heretofore mentioned, comprises a multiplicity of upright members or arms 174 having serrated upper edges which engage through slots 30 and 31' formed in the throat plate 25 in line with the said conventional, serrated members 46-47. The members comprising the retardative element have horizontal and reciprocal movement corresponding to and simultaneous with the movements of the serrated members of the conventional feeder unit, with the exception of the horizontal reciprocal movement. The horizontal movements of the retardative element, while simultaneous with the horizontal movement of the feeder, are opposite to it. In other words, when the feeder moves toward the rear, the retardative moves in the opposite direction or toward the front when both sets of serrated members are in raised positions and ready to begin such movement. This movement of the retardative member in a forward direction, when in frictional contact with the under surface of a lower fabric (Fig. 11) urges the fabric forward and prevents a creeping action bringing the end 178 of the upper layer and the end 179 of the lower layer in perfect alignment when the stitching is completed. Fig. 1 shows in plan, the spacing and position of the arms having the serrated edges 47 and 175, when same are in raised position and about to be horizontally moved apart. Figs. 4 and 8 show the position, in elevation, of the feeder unit and retardative element in their lowered position and just as they are about to move toward each other, while remaining in their lowered position. They now move together and when they arrive at the position shown in plan, in Fig. 1, they are raised to bring their serrated edges slightly above the upper surface of the throat plate 25 to contact the lower surface of the lower layer of fabric and are then given movement away from each other to the position shown in elevation in Fig. 11, and as already explained.

The form illustrated in Figs. 7 and 8 shows a means of effecting adjustments not shown in the first form. This second form is desirable in some machines where finer adjustments are required.

I claim:

A sewing machine for stitching an upper and a lower layer of material comprising, in combination, a base plate, a hook shaft mounted in bearings below the said base plate, a pair of oscillating shafts mounted longitudinally along each side of and below the said base plate, and have cam connections with the said hook shafts, a slotted throat plate having a needle orifice, secured upon the upper side of said base plate, a connecting rod pivotally attached to one of the said oscillating shafts, the free end of said connecting rod being slotted and slidably engageable with a pin secured upon a bracket attached to a second oscillating shaft, the said connecting rod being given a reciprocating horizontal movement by means of its pivotal connection with the aforesaid oscillating shaft while the second oscillating shaft imparts reciprocal vertical movement thereto, upstanding feed dogs secured to the upper face of said connecting rod and adapted to vertical and horizontal movement through the said slotted

gate plate, the said movements being imparted thereto by the said connecting rod, the said feed dogs having a rearward movement when in raised position and a forward or opposite movement when in its lowermost position, a connecting arm pivotally attached to one oscillating shaft and extending forwardly to a slotted end portion engageable with a roller pin upon a bracket arm secured upon the second oscillating shaft, the said second oscillating shaft being adapted to impart horizontal and vertical reciprocatory motion to the said connecting arm, feed dogs mounted upon the said connecting arm and engageable through the aforesaid slotted gate plate and coacting with the said connecting arm is given horizontal and vertical reciprocatory movement and when in its

raised position is given a forward movement and when in its lowermost position has a rearward movement.
